UNITED STATES PATENT OFFICE.

MORITZ GUTMANN, OF SEATTLE, WASHINGTON.

BRUSH.

1,379,976.

Specification of Letters Patent. Patented May 31, 1921.

Application filed October 23, 1920. Serial No. 419,156.

To all whom it may concern:

Be it known that I, MORITZ GUTMANN, a citizen of the United States, and residing at Seattle, in the county of King and State 5 of Washington, have invented certain new and useful Improvements in Brushes, of which the following is a specification.

This invention relates to an improvement in polishing implements, comprehending more particularly a flexible body having a soft rubbing surface, and so constructed that in use, there is provided a perfectly even bearing pressure of the soft surface on the surface to be dusted or polished, to thereby 15 avoid liability of scratching such polished surface through undue pressure in any one part of the device.

In the drawings:—

Figure 1 is a plan of the improved pol- 20 isher.

Fig. 2 is a longitudinal section through the device, showing the means by which it may be conveniently applied to the hand of the user.

Fig. 3 is an edge view of the device.

The device 1 is formed of a strip of sheep- 25 skin or other suitable skin or material, bent in its central portion as indicated at 4, to form upper and lower portions 2 and 3, so that the fur thereon is on the outside.

The edges of the skin are joined together by sewing or otherwise, leaving the end open, and a spacing member 5 is inserted in the body 1 and is formed of a comparatively 30 stiff material made in a bellows form for keeping the upper and lower surfaces normally spaced apart.

To upper surface 2 of the body and on the inside is secured a glove-shaped portion 6 to form a pocket for receiving the hand of one using the device or polisher.

In the use of the device on a polished surface, the operator, applying the polisher to the hand as described, rests the soft under-

surface of the body upon the surface to be 45 cleaned or polished, and rapidly moves the polisher over such surface. By reason of the spacing element 5, no direct pressure of the hand is upon the polishing surface of the device, so that such polishing surface of 50 the device rests upon the surface to be polished with a perfect even pressure of the soft fur material. As a result of this method of application, there is little liability of scratching the surface to be polished when 55 sharp gritty particles of dust or the like are encountered on said surface, for the reason that the polishing portion of the device rests upon the surface to be polished practically through its own weight only, and as this 60 weight is practically negligible and substantially constant, there is no pressure upon such sharp particles to cause them to scratch the surface to be polished.

A feature of the invention is the spacing 65 device, whereby the hand engaged surface of the polisher is held spaced from the polishing surface thereof, and while this spacing device is shown and preferably formed of a bellows construction, it is apparent that 70 any appropriate spacing element may be employed with equal facility.

The important detail is arranging a pol- 75 ishing surface of the device away from contact with the hand of the user, and yet fully responsive to all movements of the user's hand for the polishing operation.

Claim:

A polishing device comprising a body having a hand receiving pocket, a yielding 80 spacing member secured in the pocket for keeping the upper and lower walls thereof spaced apart, and a glove-like portion attached to the upper wall of and within the pocket.

In testimony whereof I affix my signature.

MORITZ GUTMANN.
